DERIVATIVES OF THE CYCLOPENTANO-
PERHYDROPHENANTHRENE SERIES AND
PROCESS OF MAKING SAMEThomas F. Gallagher and William P. Long, Chi-
cago, Ill., assignors to the Government of the
United States of America, as represented by the
Secretary of War and his successors in officeNo Drawing. Application June 19, 1944,
Serial No. 541,096

4 Claims. (Cl. 260—397.1)

This invention relates to hormone-like compounds of the cortical sterol type, particularly hormone-like derivatives of cyclopentanoperhydrophenanthrene having an oxygen function at carbon 11 and to an improved method of synthesizing these compounds.

It has been known for some time that the adrenal steroids were important medical compounds having particular utility in hormone therapy. These compounds are characterized by their complex molecular structure and have the following ring system:

The various processes of preparing these compounds suggested heretofore have been relatively unsatisfactory. Thus, the prior processes have been found tedious, complicated and difficult to control and the resulting yields therefrom of desired sterols too low for practical operation.

This invention has as its object a practical and economical process of preparing hormone-like cortical steroid type compounds.

Another object of this invention is to provide a method of preparing a hormone-like derivative of cyclopentanoperhydrophenanthrene having an oxygen function at carbon 11.

Other objects will be apparent from the following description of the invention.

The compounds of the present invention have an oxygen function, e. g. a hydroxyl or keto or substituted hydroxyl or keto group at the carbon 11 position of the steroid nucleus. In carrying out the invention, the compounds are prepared from cyclopentanoperhydrophenanthrene derivatives, i. e. compounds with a steroid nucleus characterized by a ketonic group at the carbon 12 position of the nucleus. Previous attempts to introduce an oxygen function at carbon 11 and still maintain a reactive keto group at carbon 12 have been unsuccessful. In prior processes, the introduction of an oxygen function at the carbon 11 position of the sterol nucleus has resulted in the formation of rearrangement products lacking an active keto group at the carbon 12 position. In order to produce the hormone-like compounds of the present invention, it is essential that the keto group remain at the carbon 12 position and remain active and be reducible to a methylene

group without destroying the oxygen function introduced at the carbon 11 position.

This invention is based on the discovery of an improved process for synthesizing cortical sterol type compounds having an oxygen function at the carbon 11 position of the nucleus. This process comprises the hydrolysis at a temperature not above about 40° C., and preferably at room temperature (20° C.), of a steroid nucleus characterized by a halogen group at the carbon 11 position and a ketonic group at the carbon 12 position. The temperature at which the hydrolysis is carried out is of utmost importance since it has been found that substantially no sterol compound having an oxygen function at the carbon 11 position and a reactive keto group at the carbon 12 position is formed by hydrolysis at temperatures above 40° C. A preferred illustrative method of practicing the present invention is as follows:

20. 1. Preparing an alkyl desoxycholate by esterifying commercial desoxycholic acid;
2. Preparing a 3-acyl derivative of the alkyl desoxycholate by partial acylation of the ester product obtained by step one;
25. 3. Preparing a 12-keto derivative of the 3-acyl-alkyl desoxycholate by oxidizing the product obtained by step two;
4. Preparing an 11-brom derivative of the 3-acyl-12-keto alkyl desoxycholate by brominating the product obtained by step three;
30. 5. Preparing 3,11-dihydroxy-12-keto cholanic acid by hydrolysis at a temperature not above about 40° C. of the 11-brom product obtained by step four.
35. 6. The desired product or epimers having a reactive keto group at carbon 12 may be separated from undesired products by fractional crystallization or by various other means known in the art. One preferred method of separation is based upon the discovery that substantially all of the desired product occurs as an epimer which forms an insoluble sodium salt while the undesired products for the most part form soluble sodium salts. The insoluble sodium salt may be isolated and treated as follows:
40. 7. Reduction of the hydrazone derivative obtained by step six whereby the hydrazone group which replaced the keto group is converted to a methylene group at the carbon 12 position of the nucleus;
50. 8. Isolation of the 3,11-dihydroxy cholanic acid obtained by step seven as an alkyl ester.

The following example serves to illustrate the present invention but is not intended to limit it thereto:

I. Methyl Desoxycholate: Commercial desoxycholic acid [3(α) 12 dihydroxy cholanic acid] is first esterified by suspending 450 grams of well dried desoxycholic acid in approximately one liter of dry methanol, adding 0.5 to 1.0 cc. of concentrated sulphuric acid in 25 cc. of methanol and, after stoppering the flask, allowing the mixture to stand at room temperature for twenty-four hours. Over this period the desoxycholic acid dissolves and the methyl ester crystallizes. The reaction mixture is then filtered with suction, the precipitate washed well by suspension in very cold methanol and dried. The material obtained melts at 97°-102° C. (corrected) and, although somewhat impure, is satisfactory for use in the further steps of the process.

II. 3(α) acetoxy 12 hydroxy methyl cholanate: 400 grams of methyl desoxycholate obtained by step I are dissolved in 750 cc. of pyridine which has been distilled over barium oxide. To this solution, 165 cc. (1.6 mole) of freshly distilled acetic anhydride are added and the mixture allowed to stand at room temperature for nineteen hours. Ice and water are next added to the pyridine solution and this mixture is allowed to stand for one to two hours. The mixture of pyridine, water and acetic acid is then decanted, extracted twice with ether, the ether extract washed twice with water and all aqueous fractions discarded. The semi-crystalline residue obtained during the reaction is then dissolved in the ether and the resulting solution extracted with small portions of five per cent sulphuric acid—five per cent sodium carbonate and finally thoroughly with water. After drying over sodium sulfate, the ether is distilled off in the usual manner. The crystalline residue obtained may be recrystallized from methanol and melts at about 124°-126° C.

III. 3(α) acetoxy 12-keto methyl cholanate: About 463 grams of the monoacetate obtained by step II are dissolved in 1500 cc. of glacial acetic acid which has been distilled over CrO_3 . Heating is required to effect solution but before oxidation the solution is cooled to room temperature. To this solution 175 grams of CrO_3 dissolved in 800 cc. of water are added with stirring over a period of one to two hours. The reaction mixture is allowed to stand with continued stirring for another hour and then about 1500 cc. of water are added slowly while stirring is continued. The crystalline mass is filtered, washed twice by suspension in water, filtered as dry as possible and dissolved in ethanol. This requires a large volume of alcohol to effect solution and since the product crystallizes with great ease, the solution must be filtered while very hot. The crystalline product obtained, 3(α) acetoxy 12-keto methyl cholanate, melts at about 147°-149° C. and is sufficiently pure for bromination purposes.

IV. 3(α) acetoxy 11 brom-12-keto methyl cholanate: About 410 grams of the keto ester obtained by step III are dissolved in one liter of stable acetic acid and 295 cc. of 6.8 N Br_2 in glacial acetic acid added (1.1 moles Br_2). The mixture is stoppered and set aside at room temperature for about five days. The reaction solution is next poured slowly from a dropping funnel into a large quantity of ice cold water with continued vigorous stirring. If the addition is made slowly and the stirring is continuous the product is sandy and easily filtrable. If the ad-

dition to the water is too fast the product is oily and washing thereof difficult. The product obtained is filtered with gentle suction and washed five times by suspension in water and vigorous mechanical stirring. The filtrates are yellow and are discarded. After the last washing, the product which is a pale yellow to white powdery solid is filtered as dry as possible and dissolved in six liters of ninety-five per cent ethanol.

V. 3,11-dihydroxy-12-keto-cholanic acid: To the alcohol solution of the brom-ketones obtained by step IV, four liters of 2.6 N sodium hydroxide are added with stirring, the bottle stoppered and set aside at room temperature for about twenty-four to thirty hours. It is important that the hydrolysis be conducted at low temperature, i. e. not above about 40° C. If the reaction mixture is heated, the resulting products do not contain (or retain) the active keto group at carbon 12. After standing, a heavy precipitate forms; the solution is next chilled overnight at -10° C. and filtered with gentle suction while still cold. The precipitate is washed twice by suspension in a small volume of ice cold water and dried without heating.

The precipitate thus obtained, contains a desired (reactive keto) epimer as an insoluble sodium salt while the filtrate retains for the most part the undesired products as soluble sodium salts. One epimer with a reactive 12-keto group does form a soluble sodium salt. It may be recovered from the filtrate by crystallization if desired, although as it is present only in small amounts its recovery has generally not been found worthwhile. This difference in solubilities of the sodium salts provides an unusually satisfactory means for separation and recovery of substantially all of the desired product characterized by the reactive keto group.

Additional insoluble sodium salt may be recovered from the filtrate or reaction mixture by acidifying the filtrate under ether, extracting with ether, washing the extract with water, drying the washed extract over sodium sulfate, distilling off the ether, dissolving the oily residue in ethanol, neutralizing with caustic alkali, diluting with water and allowing the product to stand at about -10° C. The insoluble sodium salt obtained as a precipitate is then washed by suspension in cold water and dried without heating.

VI. Hydrazone of the insoluble sodium salt of 3,11-dihydroxy-12-keto cholanic acid: About 100 grams of the dried insoluble sodium salt obtained by step V are dissolved in 1400 cc. of absolute ethanol under reflux. To the resulting solution 25 cc. of 100 per cent hydrazine hydrate are added and refluxing continued for one hour. Approximately two-thirds of the alcohol is then distilled off and the residual solution allowed to crystallize. The mother liquors from this crop of crystals upon further concentration yield several additional crops of hydrazone. The hydrazone obtained is quite hygroscopic and should be stored in a dessicator.

VII. Wolff-Kishner reduction of the 3,11-dihydroxy-12-keto cholanic acid hydrazone: About 5 grams of the hydrazone obtained by step VI are introduced into a glass or steel bomb tube and 50 cc. of sodium ethylate prepared from 3 grams of sodium added along with 0.5 cc. of one hundred per cent hydrazine hydrate. The tube is then sealed and heated at 200° C. for five hours. After

cooling, the tube is opened and the contents rinsed out with alcohol, water or other solvent.

VIII. Isolation of 3,11-dihydroxy cholanic acid as the methyl ester: The reaction product obtained by step VII is preferably rinsed from the bomb tube with ninety-five per cent ethanol so that the final volume is one liter of ethanol for each 40 grams of the sodium salt hydrazone reduced. This solution is heated and neutralized to phenolphthalein with dilute aqueous hydrochloric acid and an additional amount of water sufficient to bring the volume to two liters added. One liter of 0.3 N barium hydroxide is next added, to the hot aqueous alcohol solution and finally one liter of hot water added slowly with constant stirring. The flask is then stoppered and allowed to cool overnight. The insoluble barium salt is removed by filtration and the filtrate containing soluble barium salts acidified under ether and extracted twice with fresh portions of ether. The ether solution is washed thoroughly with water,

evaporated to dryness, and traces of water removed from the residue by distilling benzene two or three times from the residue. (The free acid may be isolated from this fraction by acidification with excess hydrochloric acid and filtration.) The oily material is preferably dissolved in dry methanol, a small amount of concentrated sulphuric acid added, and the solution allowed to stand at room temperature for from four to five hours or overnight to effect esterification. The methanol solution is poured into ether, extracted with sodium carbonate solution and with water. The neutral fraction is then concentrated and the 3,11-dihydroxy methyl cholanate obtained as a precipitate recrystallized from a benzene-petroleum ether mixture. The desired product melts at 132°-134° C. and has $[\alpha]_D = +13^\circ$ (ethylacetate), $[\alpha]_D = +7^\circ$ (chloroform).

The following table of formulae serves to illustrate the reaction described above:

Having thus described our invention, what we claim as new and wish to secure by Letters Patent is:

1. A process for the production of 3,11-dihydroxy cholanic acid which comprises subjecting 3(α)-acetoxy-11-brom-12-keto methyl cholanate to alkali hydrolysis at a temperature not above about 40° C. to form an alkali salt of 3,11-dihydroxy-12-keto cholanic acid, reacting said salt with hydrazine to form the 3,11-dihydroxy-12-hydrazone derivative thereof and thereafter reducing said 12-hydrazone derivative to form 3,11-dihydroxy cholanic acid.

2. The compound 3,11-dihydroxy cholanic acid.

3. A process for the production of 3,11-dihydroxy cholanic acid which comprises subjecting 3(α)-acetoxy-11-halo-12-keto-alkyl cholanate to alkali hydrolysis at a temperature not above about

40° C. to form an alkali salt of 3,11-dihydroxy-12-keto cholanic acid, reacting said salt with hydrazine to form the 3,11-dihydroxy-12-hydrazone derivative thereof and thereafter reducing said 12-hydrazone derivative to form 3,11-dihydroxy cholanic acid.

4. A process for the production of 3,11-dihydroxy cholanic acid which comprises hydrolyzing 3(α)-acetoxy-11-brom-12-keto methyl cholanate with sodium hydroxide at a temperature of about 20° C. to form an insoluble sodium salt of 3,11-dihydroxy-12-keto cholanic acid, reacting said salt with hydrazine to form the 3,11-dihydroxy-12-hydrazone derivative thereof, and thereafter reducing said 12-hydrazone derivative to form 3,11-dihydroxy cholanic acid.

THOMAS F. GALLAGHER.

WILLIAM P. LONG.
